UNITED STATES PATENT OFFICE.

HARRY HESS, OF GLENGARRY, MONTANA.

RAILROAD-TIE.

1,143,964.

Specification of Letters Patent. Patented June 22, 1915.

Application filed March 31, 1915. Serial No. 18,372.

To all whom it may concern:

Be it known that I, HARRY HESS, a citizen of the United States, residing at Glen-garry, in the county of Fergus and State of 5 Montana, have invented certain new and useful Improvements in Railroad-Ties, of which the following is a specification, reference being had to the accompanying drawings.

10 My invention relates to railway ties, and particularly to composite ties. The primary object of my invention is the provision of a tie including a tie body within which is disposed one or more wooden cores, the tie being adapted to have the rails supported thereon spiked to the wooden cores or filling members thereby avoiding the difficulty usually found in metallic ties of attaching rails to the metallic ties and also avoiding 20 the rigidity of the ordinary metallic tie.

A further object of my invention is the provision of a tie of the character described which is so formed that wooden filling pieces may be driven in and wedged in place in the 25 opposite ends of the tie so as to hold firmly in position and prevent any outward accidental movement thereof.

Still another object of my invention is the provision of a tie of this description so 30 formed that the wooden filling pieces or cores may be removed when "spike killed" to permit the driving of other wooden filling pieces, and further which will permit the filling pieces to be driven in from time to 35 time farther and farther into the tie to permit the redriving of spikes.

Other objects will appear in the course of the following description.

My invention is illustrated in the accompanying drawings, wherein:

Figure 1 is a top plan view of a tie, one end of the tie being partly broken away; Fig. 2 is a side elevation of the tie shown in Fig. 1, partly in section.

45 Referring to these drawings, 2 designates a metallic tie which is practically rectangular in cross section. The top web 3 of this outer shell 2 or body of the tie is cut away as at 4 at two places at a distance apart equal 50 to the gage of the track. The bottom and side webs 5 and 5^a of the body or shell 2 are thickened as at 6 adjacent its opposite ends, these thickened portions each having a downwardly and outwardly inclined face 7 55 forming a wedging surface, this face 7 converging toward the axial center of the tie.

Forced into the opposite ends of the body 2 are the filling pieces 8. It will be seen that the thickened portions 6 of the tie extend from one extremity of the tie inwardly beyond the corresponding opening 4 for the rail, and therefore that these wooden filling pieces or cushions are disposed beneath these openings 4. It will likewise be seen from Fig. 1 that preferably the upper web 3 on each side of the corresponding opening 4 is provided with lateral offset notches 9 adapted to receive the spikes 10 which hold the rail 11 in place.

In practical use the filling pieces or cushions 8 are driven into place in the ends of the tie and wedged against the upper and side webs by reason of the inclined faces 7 of the thickened portions 6. The rail is then disposed upon the tie in the ordinary 75 manner, and the spikes 10 driven into the wood of the filling pieces. If in the course of time it is necessary to re-spike the rail for any reason, and the spike openings in the filling pieces have become enlarged or 80 are rusty or damaged by rust, the cores or filling pieces 8 may be driven farther in, or, if desired, these filling pieces may be withdrawn and new filling pieces disposed within the tie. Inasmuch, however, as these filling pieces 8 are surrounded by the metal of the tie they are protected to a considerable degree and will last for a relatively long time, and further, it is possible, because of the protection afforded these pieces, 90 to use treated timber. Under ordinary circumstances the use of treated timber is not economical as the redriving of spikes tends to "spike-kill" the tie in a relatively short time. It will further be noted that the rail 95 rests down within the recess 4 so that it is held accurately to gage and prevented from lateral movement. It will further be noted that the inner end of each thickened portion 6 terminates abruptly and that as the wood of which the filling pieces are preferably composed is more or less elastic that if the filling piece be driven in so that its inner end lies beyond the inner end of the thickened portion 6, the inner extremity of the filling piece will expand slightly so as to engage over this end thus holding the filling piece firmly from outward movement but permitting the further inward movement of the filling piece.

By my invention I provide a very simple and cheap form of tie having the good

qualities of a wooden tie combined with the good qualities of a metallic tie. Furthermore, it will be seen that I avoid the use of any other device except spikes for holding the rail in place, and thus do away with the difficulty experienced in the case of metallic ties. Furthermore, I provide for overcoming the difficulties due to re-spiking and "spike-killing." The wooden filling

10 pieces not only act as cores or fillers to which the rail is spiked, but also act as cushioning means for the rail, giving the rail the yieldingly elastic support demanded in railroad practice, and these filling
15 pieces further act to deaden the sound due to the travel of a train over metallic ties.

It will be noted that the filler piece is exposed under the rail so as to allow room for wear. The thickened portions 6 on the
20 side walls should both be on the same side so that the filler pieces may be exchanged when necessary as regards the ends of the tie, and the good side of the filling piece be disposed against the rail. I have found in
25 practice that the shoulders formed at the ends of the thickened portions should be not less than one-half an inch and not more than one inch. It will of course be understood that the cuts 4 on the tie supporting
30 the rails at the joints should be made to correspond with the sized angle bars that are used on the road using the ties.

Having thus described my invention, what I claim is:

35 1. A tie comprising a hollow shell, one wall of which is thickened, the inner face of said wall being inclined away from the exterior of the tie and toward the middle thereof, relatively elastic filling pieces disposed within the tie and having wedging engagement with said wall.

40 2. A tie comprising a hollow metallic shell, one wall of which is thickened adja-

cent opposite ends, each thickened portion having an inwardly and medially inclined 45 inner surface, the upper web of the shell being cut away adjacent opposite ends, and relatively elastic filling pieces forced into opposite ends of the shell and held in engagement therewith by wedging contact 50 with the inner surface of the thickened portion.

3. In a tie, a hollow metallic shell including a bottom wall and a top wall, the top wall being transversely cut away adjacent its ends for the reception of rails, the bottom wall having wedging faces confronting the cut-away portion, and wooden filling pieces driven into the ends of the tie and having wedging engagement with said 60 faces, the side walls of the opening in the upper web being formed with spike-receiving notches.

4. A railway tie comprising a hollow shell of relatively non-yielding material and 65 open at its opposite ends and cut away upon its upper face to form rail seats, one wall of the shell being formed at opposite ends with thickened portions extending toward the middle of the shell and beyond said rail 70 seats and terminating abruptly, the inner face of each of said walls being inclined away from the exterior of the tie and toward the middle thereof, and wooden filling pieces interposed within the ends of the tie 75 and having wedging engagement with said thickened inclined walls and adapted to extend over the abrupt ends of said thickened portions to thereby cause the filling pieces to be held in place.

In testimony whereof I hereunto affix my signature in the presence of two witnesses.

HARRY HESS.
